STREAMER ADAPTED FOR TOWING BY
AIRCRAFTCharles D. Young, Haverford, Pa., assignor to
Kellett Autogiro Corporation, Philadelphia,
Pa., a corporation of Delaware

Application May 11, 1933, Serial No. 670,390

5 Claims. (Cl. 40—127)

This invention relates to streamers adapted for towing by aircraft, and more particularly to streamers bearing words or symbols displayed thereon in such manner as to constitute a sign 5 clearly legible from the ground and therefore useful for the purpose of advertising.

With streamers of the type now used for advertising, it has been found that there are definite limitations on the length of the sign to be displayed. Where attempts have been made to exceed a particular length of sign, say, thirty letters or thereabouts, for a particular type of towing aircraft, certain difficulties have been encountered. Either the streamer is caused to sag 15 or twist, making the sign difficult to read from the ground, or a drag element of prohibitive resistance has to be trailed at the rear of the streamer. To be effective for advertising purposes, the streamer must have stability and be maintained in a substantially vertical plane with its longitudinal axis substantially horizontal. Such stability is ordinarily obtained by the use of drag elements at the rear of the streamer proportioned, as to the degree of resistance offered, 20 according to the length and height of the sign. There are obvious limitations, however, upon the weight of the streamer and its resistance to towing.

The object of my invention is to provide a 30 streamer so designed and constructed that it may extend to a greater length than those heretofore used, and yet nevertheless be within the limitations of weight and resistance mentioned above, and which will also maintain its stability when 35 towed in the air. To this end my invention is characterized by the provision of a plurality of drag elements so spaced and connected to the framework of the streamer as to cause it to be held throughout its length against twisting or 40 sagging.

A further object of the invention is to incorporate the drag elements in the streamer in such manner as to prevent obstruction of the sign carried thereon.

Other more specific objects and advantages 45 characterizing my invention will become more fully apparent from the description hereinafter set forth of certain examples or embodiments of my invention, the description having reference 50 to the accompanying drawing, whereof:

Fig. I represents a side elevation of a streamer of my invention with portions thereof broken away to permit the drawing to be on a relatively large scale.

Fig. II represents a cross section of the same,

taken as indicated by the lines II—II of Fig. I; and,

Fig. III represents portions of a modified form of streamer embodying my invention.

With reference to the streamer illustrated in Fig. I, it will be observed that the same comprises a rectangular skeleton framework including rigid vertical members 1, 2 disposed in spaced parallel relation and longitudinal non-rigid members 3, 4 parallel to each other. Preferably the vertical members 1, 2 may take the form of bamboo poles, whereas the upper and lower longitudinal members 3 are desirably made of stout cord, and the intermediate longitudinal members 4 of finer cord. In the particular example illustrated, the framework is divided longitudinally by the vertical members 1, 2 into a series of panels a. From the upper and lower ends of the leading vertical member 1, diagonal tension members 5 extend rearward, intersecting each other at the rear of the first panel and joining the upper and lower ends of the vertical member 2 at the rear of the second panel. The diagonal tension members 5 are continued in the same manner throughout the length of the streamer.

At the forward or leading end of the streamer, I may employ a loop bridle 6 joining the upper and lower ends of the foremost vertical member 1 and forming therewith a triangular connection between the tow line 7 and the framework of the streamer. The tow line 7 terminates in an eye or thimble 8 surrounding the bridle 6 and slideable thereon. The letters or symbols 9 to be displayed on the framework of the streamer are secured by any suitable means to the intermediate longitudinal members 4, or they may extend from the upper longitudinal 3 to the lower longitudinal 3, the present invention not being concerned with the mode of attachment of the display sign to the framework.

At spaced intervals throughout the length of the framework, I employ vertical members of greater height than the other, the short vertical members being designated at 1, and the longer vertical members being designated at 2, the latter 45 extending above the uppermost longitudinal member 3 and preferably also below the lowermost longitudinal member 3. While in Fig. I of the drawings only eight panels a are represented, it will be understood that the invention 50 contemplates a streamer which is very much longer in proportion to its height, and the elongated vertical members 2 may be, and desirably are, spaced at considerably greater intervals than as represented.

To the upper ends of the elongated vertical member 2 there are attached drag elements 10a, 10c, and 10e, which may take the form of ordinary wind cones. Corresponding drag elements 5 10b, 10d, and 10f are also shown attached to the lower ends of the elongated vertical members 2; and to the rear end of the framework an additional pair of drag elements 10g, 10h are attached. Drag elements 10a, 10c, and 10e have 10 associated therewith diagonal tension members 14 which lead from points along the top edge of the framework upward and rearward to the upper ends of the elongated vertical members 2, thereby transmitting the tension stresses in a 15 substantially longitudinal direction along the top edge of the streamer.

By thus providing a series of spaced drag elements along the upper edge of the framework, the uppermost longitudinal member 3 is tensioned with forces applied at intervals of its 20 length and is maintained taut during flight of the streamer without tending to sag or twist in the intermediate regions between the ends of the framework. Moreover, the total resistance offered by the series of drag elements 10a, 10c, 25 10e, and 10g is considerably less than the resistance which would be required of a single drag element trailed at the rear of the framework and capable of doing the same work. Likewise 30 the drag elements 10b, 10d, and 10f at the lower edge of the framework assist in maintaining the stability of the medial portion of the framework and may be found useful in addition to the upper series of drag elements.

35 Irrespective of the number and disposition of the drag elements along the streamer, I prefer to proportion these elements so that they increase progressively in resistance from the forward end toward the rear of the framework. Thus in Fig. I the first pair of drag elements 10a, 40 10b would be relatively small, the next pair 10c, 10d would be larger, the next pair 10e, 10f still larger, and the trailing drag elements 10g, 10h considerably larger than any of the others. In 45 this manner each drag element is made to a size just sufficient to perform the work required of it and adequate stability is obtained with a minimum of total resistance to towing.

It being important to maintain the center of 50 gravity of the framework well below the towing axis, weights 15 are placed at the lower edge of the framework, conveniently at the lower corners thereof, where they are attached to the bottom ends of the leading and trailing vertical members 1. In order, however, to minimize the 55 total weight of the streamer, I may, as shown in Fig. III, employ in lieu of, or in reduction of, weights, lift elements 16, such as a kite, attached by a line 17 to the upper edge of the framework. The lift elements 16 may also be proportioned 60 as to resistance offered, and serve not only to lower the effective center of gravity, but also assist in maintaining the desired degree of tautness in the framework.

65 In Fig. III there is shown a further modification in that a single drag element 10x is trailed

at the rear of the streamer, the same being slidably connected to a trailing loop 18 which joins the upper and lower ends of the rearmost vertical member 1.

While I have described certain specific examples of the practice of my invention, it will be apparent, especially to those skilled in the art, that various changes may be made in the particular form of the streamer, its framework, and the nature and disposition of the drag elements, 10 all without departing from the spirit of the invention as defined in the annexed claims.

Having thus described my invention, I claim:

1. A streamer adapted for towing by aircraft comprising a tow line, an elongated skeleton 15 framework attached thereto, and drag elements at spaced intervals along the length of said framework, said drag elements progressively increasing in resistance from the forward end toward the rear of the framework.

2. A streamer adapted for towing by aircraft comprising a tow line, an elongated skeleton framework attached thereto, and drag elements disposed above and below the upper and lower edges of said framework at spaced intervals 25 therealong, said drag elements progressively increasing in resistance from the forward end toward the rear of the framework.

3. A streamer adapted for towing by aircraft comprising a tow line, a framework attached 30 thereto including spaced rigid vertical members and non-rigid parallel longitudinal members joining said vertical members, certain of said vertical members extending above the uppermost longitudinal member and below the lowermost 35 longitudinal member, drag elements disposed at the extremities of said latter vertical members, and an additional drag element trailed from the rear end of said framework.

4. A streamer adapted for towing by aircraft 40 comprising a tow line, a framework attached thereto including spaced rigid vertical members and non-rigid parallel longitudinal members joining said vertical members, certain of said vertical members extending above the upper- 45 most longitudinal member with their extremities connected by diagonal tension members to the top edge of said framework, drag elements disposed at the upper ends of said latter vertical members, and an additional drag element trailed 50 from the rear end of said framework.

5. A streamer adapted for towing by aircraft comprising a tow line, a framework attached thereto including spaced rigid vertical members and non-rigid parallel longitudinal members 55 joining said vertical members, certain of said vertical members extending above the uppermost longitudinal member and below the lowermost longitudinal member, drag elements arranged in pairs at spaced intervals along said framework 60 and attached to the extremities of said vertical members, said drag elements progressively increasing in resistance from the forward end toward the rear of the framework.
